Primary Examiner — Holly E Thurman*Assistant Examiner* — Bailey M Knotts*(74) Attorney, Agent, or Firm* — Ying-Ting Chen(57) **CLAIM**

The ornamental design for a flashlight as shown and described.

DESCRIPTION

FIG. 1 is a front view of a flashlight showing my new design;
FIG. 2 is a rear view thereof;
FIG. 3 is a left view thereof;
FIG. 4 is a right view thereof;
FIG. 5 is a top view thereof;
FIG. 6 is a bottom view thereof;
FIG. 7 is a top, right front perspective view thereof; and,
FIG. 8 is a bottom, right rear perspective view thereof.
The broken line portion of the figure drawings is included to
show portions of the flashlight and forms no part of the
claimed design.
